UNITED STATES PATENT OFFICE.

JACOB WAMPACH AND HENRY WAMPACH, OF JORDAN, MINNESOTA.

MOUNTING FOR SILO-DOORS.

1,200,280.

Specification of Letters Patent.

Patented Oct. 3, 1916.

Application filed April 20, 1916. Serial No. 92,447.

To all whom it may concern:

Be it known that we, JACOB WAMPACH and HENRY WAMPACH, citizens of the United States, residing at Jordan, in the county of Scott and State of Minnesota, have invented certain new and useful Improvements in Mountings for Silo-Doors; and we do declare the following to be a full, clear, and exact description of the invention, such 10 as will enable others skilled in the art to which it appertains to make and use the same.

Our invention which relates broadly to improvements in silos has for its object to 15 provide a supporting frame applicable to the numerous doors thereof for hingedly supporting said doors and at the same time serving to form a ladder by means of which a person may ascend to any required level.

With this general object in view, the invention resides in certain novel features of construction and in unique combinations of parts to be hereinafter fully described and claimed, the descriptive matter being supplemented by the accompanying drawings 25 which constitute a part of this application and in which:

Figure 1 is a front elevation of a portion of a silo showing the application of a pair 30 of improved frames thereto; Fig. 2 is a horizontal sectional view taken on the plane indicated by the line 2—2 of Fig. 1 showing one of the doors open and another closed; Fig. 3 is a vertical section as viewed on the 35 planes of the line 3—3 of Fig. 1; and Fig. 4 is a perspective view of one of the aforesaid frames.

In specifically describing the structure shown in the drawings above briefly described, similar characters will be placed on corresponding parts throughout the several views and reference will be herein made to the numerous elements by their respective indices. To this end, the numerals 1 designate the vertically alined door frames of a silo 2, such frames being of the usual or any preferred shape and being normally closed by suitably constructed doors 3 which are adapted to open inwardly. Each door 50 3 is mounted on a frame 4 whose construction constitutes the gist of the present invention.

Each frame 4 includes a pair of horizontal metal bars 5 spaced outwardly from the 55 frame 1, one end of said bars being bent rearwardly at right angles as disclosed at 6

and curled upon themselves to form upright hinge knuckles 7 receiving therein pintles 8 carried by one upright side of the door frame. The other ends of the bars 5 are 60 riveted or otherwise secured to an upright bar 9 and the uppermost of said bars 5 projects beyond the bar 9 as shown at 10, this portion overlying a metal finger 11 which is secured to and projects forwardly from the 65 frame. This finger and the extension 10 serve to support the free end of the bars 5 to prevent sagging thereof when said bars are in use as a ladder. A pair of arms 12 extend rearwardly from the intermediate portions of the aforesaid bars 5, said arms being preferably constructed of metal bars and having laterally bent ends 13 which are riveted or otherwise secured to said bars 5. The free ends of the arms 12 are curled 70 upon themselves to provide hinge knuckles 14 alining vertically with other knuckles 15 carried by the door 3, pintles 16 being passed through said knuckles whereby the door is hingedly connected with the arms 12. 75 For the purpose of imparting the necessary rigidity to the arms 12 and preventing sagging thereof when the weight of a person is supported by either of the bars 5, said arms are preferably connected by crossed braces 80 17 whose ends are riveted thereto.

The edge of the door 3 is provided with a projecting flange 18 adapted to limit the closing movement of said door, and for the purpose of holding the latter in closed position, a suitable latch 19 is provided, said latch preferably consisting of a rock shaft 20 mounted rotatably and slidably in a bearing 21 secured to the frame 1, one end of said shaft having thereon a cam 22, while 95 the other end thereof is equipped with an operating lever 23. In most cases, for ease of construction, the lever 23 and cam 22 will be formed by bending the ends of the shaft 20 as shown, but it will be obvious that other structures may well be provided and in fact totally different types of latches may be employed if found desirable.

In order to release the latch 19, the lever 23 is raised and shifted longitudinally to 105 remove the cam 22 from the inward path of the bar 9, said cam being normally in contact with the rear side of said bar. When this has been done, the entire frame 4 may be swung inwardly through the door 110 frame 1, thereby opening the door 3 as shown in Fig. 2. By constructing the frame

4 in the manner shown and described, it
will be highly efficient and durable yet it
may be inexpensively manufactured and
easily applied by unskilled hands. The im-
5 proved frames will be employed on the nu-
merous doors 3 and not only serve as means
for holding said doors closed or open as the
case may be, but they also act as a ladder by
means of which a person may ascend to any
10 desired door for entering the silo there-
through.

From the foregoing, taken in connection
with the accompanying drawings, the con-
15 struction, manner of operation and advan-
tages of the invention will be readily un-
derstood without requiring a more extended
explanation. In conclusion, however, we
will state that although certain specific de-
20 tails of construction have been shown and
described for accomplishing probably the
best results, numerous changes may be made
within the scope of the invention as claimed
without sacrificing the main advantages
25 thereof.

25 We claim:

1. The combination with the door frame
of a silo and an inwardly opening door
therefor; of an upright supporting frame
30 hinged to one side of said door frame and
adapted to swing into the silo through said
frame, a hinge connection between the door
and said supporting frame, releasable means
35 for normally preventing swinging of said
supporting frame, and coacting stops on the
two frames for preventing sagging of the
free end of said supporting frame, whereby
the latter may serve as a section of a ladder.

Copies of this patent may be obtained for five cents each, by addressing the "Commissioner of Patents,
Washington, D. C."

2. The combination with the door frame
of a silo and an inwardly opening door
thereof; of a supporting frame hinged to 40
one side of said door frame and adapted to
swing into the silo through said frame, said
supporting frame including a plurality of
horizontal bars adapted to serve as ladder
rungs, a hinge connection between the door 45
and said supporting frame, releasable means
for normally preventing swinging of said
supporting frame, and a rigid stop project-
ing from said door frame and underlying
one of the horizontal bars of said support- 50
ing frame to prevent sagging of the latter.

3. A frame for supporting silo doors, said
frame comprising upper and lower hori-
55 zontal bars having means at one end for hing-
ing them to one side of the door frame, an
upright bar secured at its ends to the other
ends of said horizontal bars, one of the last
named ends being extended beyond said up-
right bar and being adapted to overlie a 60
stop fixed to the door frame to prevent
sagging of the supporting frame, and a pair
of rigid arms secured to and extending later-
ally from the intermediate portions of said
horizontal bars, said arms having means at 65
their free ends for hingedly connecting them
with the door.

In testimony whereof we have hereunto
set our hands in presence of two subscrib-
ing witnesses.

JACOB WAMPACH.
HENRY WAMPACH.
